UNITED STATES PATENT OFFICE.

BEAT KUHNE, OF LEWISTOWN, MONTANA.

MILK-BOTTLE CAP.

Application filed November 14, 1921. Serial No. 515,067.

To all whom it may concern:

Be it known that I, BEAT KUHNE, a citizen of the United States, residing at Lewistown, in the county of Fergus and State of 5 Montana, have invented certain new and useful Improvements in Milk-Bottle Caps, of which the following is a specification.

This invention relates to bottle closures and more particularly to a cap for milk 10 bottles or jars and the primary object of the invention is the provision of novel means for permitting the convenient removal of the cap when so desired, without the aid of any extraneous tools, said means being associated with the cap without the use of metal, as now used in caps provided with pulling tabs, so that the possible contamination of 15 the milk by contacting with metal will be obviated.

Another object of the invention is the provision of an improved finger grip of flexible material for facilitating the removal of a cap from milk bottles or jars, the finger grip having a novel formation so that the 20 same can be readily grasped by the fingers and which consists of a flexible disc having its lower face substantially conical shaped and connected at its apex portion to the cap, said disc defining wide flaring flexible finger 25 gripping flanges, the lower inclined faces of which permit the ready engagement thereof by the fingers.

A still further object of the invention is the provision of a novel means for associating 30 said pulling disc with a milk bottle cap and for forming the disc out of such material that can be readily grasped by the fingers of the user and which will not tear or become separated from the cap.

A still further object of the invention is the provision of a novel means for facilitating the removal of a closure for milk bottle jars which is of simple and durable construction and one which can be associated 40 with ordinary milk bottle caps and placed upon the market at a reasonable cost.

With these and other objects in view, the invention consists in the novel construction, arrangement and formation of parts, as will 50 be hereinafter more specifically described, claimed and illustrated in the accompanying drawings, forming a part of this specification, in which drawings:

Figure 1 is a perspective view of a cap 55 constructed in accordance with this invention in use.

Figure 2 is a top plan view of a cap constructed in accordance with this invention.

Figure 3 is a top plan view of a slightly modified form of cap. 60

Figure 4 is a top plan view of a further slightly modified form of cap.

Figure 5 is a diametric section taken on the line 6—6 of Figure 2.

Figure 6 is a diametric section taken on 65 the line 6—6 of Figure 3, and

Figure 7 is a diametric section taken on the line 7—7 of Figure 4.

Referring to the drawings in detail, wherein similar reference characters designate 70 corresponding parts throughout the several views, the letter A indicates a milk bottle cap and B, the novel device for permitting the ready lifting of the cap from a milk bottle, which is designated in the 75 drawings by the letter C. The milk bottle C of course, forms no part of the invention and has merely been shown for illustrating the use of the cap, and this bottle is provided with the usual restricted throat 8 in 80 which the cap A is adapted to be placed.

The cap A is constructed in the usual manner and formed of the usual material and consists of a disc or circular shaped body 10 formed of a plurality of plies of relatively strong card board or the like, suitably oiled or waxed to render the same impregnable to liquid. 85

The lifting or pulling knob or device B can be constructed of any preferred material 90 and as shown in Figures 2 and 3 of the drawings, it is contemplated of making the same of soft rubber so that the same may be readily grasped by the fingers.

In the form shown in Figures 2 and 3, the 95 lifting device or knob B consists of an attaching base 15 and a pulling or finger gripping piece 20. The base 15 and the pulling or finger gripping piece 20 are disposed in superposed relation and are integrally connected together and each of the same are of a substantially disc shaped formation with their meeting faces tapered to present a substantially conical configuration, and the apex portions of the conical faces 100 are connected together and this forms relatively wide flaring flanges 21 which permit the gripping thereof by the fingers. The inclined surface 22 of the top disc or pulling section 20 forms a guide for the fingers or 105 finger nails so that a ready grip can be had on the same. The flaring flanges of the top 110

disc or finger gripping section 20 form flexible compressible tabs 22. The base section 15 is connected to the top 10 adjacent to one edge thereof in any preferred manner and it is desired that a suitable adhesive be used such as glue or the like for connecting the base with the cap.

In the form shown in Figures 2 and 5 of the drawings, the cap 10 has the upper ply 10 thereof provided with a circular notch 16 in which the base 15 is fitted and this notch can have a suitable adhesive placed directly therein. The notch is formed relatively shallow so that a portion of the base 15 will protrude out of the same and all of the finger gripping or top disc section 20.

In the form shown in Figures 3 and 6 of the drawings, the base section 15 is secured directly to the upper surface of the cap 10 20 and thus the necessity of cutting or notching the upper face of the cap is eliminated.

In the form shown in Figures 4 and 7 of the drawings, the pulling portion which is designated by the numeral 25 in these figures is connected directly to the cap which is designated by the numeral 30 in these figures. The knob 25 is of course formed of the same material as the cap 30 and the top ply of the cap 30 may have the projection 25 formed 30 integral therewith and the periphery of this projection which is disc shaped in plan is undercut as at 26 to provide the tapered flange 27. The lower face of the projection or knob 25 is also of a substantially conical 35 shape and the apex portion of the lower conical face is integrally connected with the cap. By undercutting the section or knob 25, the flexible tapered flange is formed and it will be seen that this tapered surface 40 forms a guide for the finger or finger nails.

In use of the improved invention, when it is desired to remove a cap from the bottle, it is merely necessary to grasp the outside of the top disc or pulling knob 20 or the knob 45 25 and give the same a pull, which will effectively lift the cap from the throat 8 of the bottle C. By this construction, the use of metal clips or the like for holding pulling knobs or discs in position is eliminated, and 50 it can be seen that a simple and durable means has been provided which will conveniently permit the ready lifting of the cap from the neck or throat of a bottle.

Changes in details may be made without 55 departing from the spirit or scope of this invention; but,

I claim:

1. As a new article of manufacture, a milk bottle closure comprising a sealing disc, 60 a finger gripping disc associated therewith having a lower conical face with the apex

portion thereof connected with the disc, the lower conical face of said pulling disc providing flexible finger gripping flanges and guide surfaces for the fingers. 65

2. As a new article of manufacture, a milk bottle closure comprising a sealing disc, a pulling knob associated with the disc formed of flexible material and including a disc shaped body having a lower inclined 70 face connected at its central portion with the disc, defining annular flexible flanges overhanging said sealing disc.

3. As a new article of manufacture, a bottle closure comprising a sealing disc, a 75 pulling knob associated with the disc adjacent to one edge thereof comprising a disc shaped body having the lower face thereof tapered and connected at its axial center with the disc, the tapered lower face defining annular 80 overhanging flexible finger gripping flanges.

4. As a new article of manufacture, a bottle closure comprising a sealing disc, means disposed adjacent to one edge of the disc for facilitating the removal thereof 85 from the bottle including an attaching base and a finger gripping disc, the attaching base being adapted to be connected directly with the sealing disc, the meeting faces of the attaching base and the pulling disc being 90 conical shaped and integrally connected at their apex portions.

5. As a new article of manufacture, a milk bottle closure comprising a sealing disc, and a means for facilitating the removal 95 of a disc from a milk bottle including a disc shaped attaching base for connection with the sealing disc adjacent to one edge thereof and a finger gripping disc, the said means for facilitating removal of 100 the sealing cap from the bottle being formed of relatively soft rubber, the attaching disc and the finger gripping disc having the meeting faces thereof conical shaped and integrally connected together at their apex 105 portions, said conical face of said finger gripping disc defining a guide surface and overhanging flexible finger gripping flanges.

6. A jar closure comprising a sealing disc having its upper face adjacent to one edge thereof provided with a circular indentation, a device for facilitating the removal of the sealing disc from the bottle including a disc shaped attaching base fitted in said indentation and secured therein, a 110 pulling disc, the meeting faces of the attaching disc and pulling disc being flared outwardly from their axial center toward their outer edges, the discs being connected together at their axial centers. 115

BEAT KUHNE.
